UNITED STATES PATENT OFFICE.

JOHN J. MULVANEY, JR., OF RIVERSIDE, ASSIGNOR TO JOHN W. STREHLI,
TRUSTEE, OF CINCINNATI, OHIO.

BARREL-HEADING MACHINE.

SPECIFICATION forming part of Letters Patent No. 437,785, dated October 7, 1890.

Application filed June 2, 1890. Serial No. 353,963. (No model.)

To all whom it may concern:

Be it known that I, JOHN J. MULVANEY, Jr., a citizen of the United States, residing at Riverside, in Hamilton county, and State of Ohio, 5 have invented certain new and useful Improvements in Barrel-Heading Machines, of which the following is a specification.

The object of my invention is to provide a cheap, simple, effective, and durable machine 10 for placing the heads in barrels, casks, and other similar tight vessels.

It consists, essentially, in providing a series 15 of bearing-pieces or segments which constitute a compressor which encircles the part of the barrel or cask to be headed, and while so encircling said part are held in such position by suitable mechanism, said parts being then forced or pulled downward, said movement forcing said bearing-pieces comprising 20 the compressor to hug and impinge against all the staves of the barrel or cask, consequently bringing said staves inward and together (to form an unbroken periphery) and around the head, which is suitably held by 25 the operator, the head being forced into the croze in the staves ready to have the hoop placed thereon. Said parts may then be released. Any form of mechanism may be employed to operate these bearing-pieces forming 30 the compressor and the mechanism which holds them in position when encircling the barrel and when they are forced downward. In the present instance I have shown and described them as attached to one form of mechanism, which is preferably placed below the 35 floor of the shop.

In the accompanying drawings, forming part of this specification, Figure 1 is a sectional view taken at the line 1 1 of Fig. 2, the 40 upright arms being, however, shown, as well as a side view of my improvements, a barrel being shown in the machine. Fig. 2 is a top view of one form of mechanism for operating the machine, the upright arms being omitted 45 and the floor being removed. Fig. 3 is a perspective view of one of the bearing-pieces. Fig. 4 is a view in elevation of my improved devices around a barrel, being partly broken away at the top on one side to show the barrel-head, which is in section, one of the bear-

ing-pieces, and the encircling-ring, which are also in section. Fig. 5 is a view in elevation of my improved devices around a barrel as they appear when the head has been forced into the barrel, the parts being partly broken 55 away at the top on one side to show the barrel-head forced into position. Fig. 6 is a top view of my improved devices shown in Fig. 5. Fig. 7 is a top view of a plate and disk and the mechanism which forces all the upper 60 upright arms carrying the bearing-pieces inward or outward simultaneously. Fig. 8 is a view of a modification of my device, rollers being shown to take the place of the bearing-pieces. Fig. 9 is a view of modified mechanism 65 for keeping the bearing-pieces in position against the barrel when the staves are being forced together.

I will first describe my improved devices and then one form of mechanism for operating the same.

In the drawings, A represents the barrels. B represents the upright arms of the machine, the upper parts of which I peculiarly construct. To the upper parts of these arms 75 I attach in any suitable manner the bearing-pieces C. I preferably connect them by a screw-and-bolt connection. They may be welded on the arms, if desired. I may use as many of the arms with bearing-pieces attached as I desire, in the present instance six being shown. These bearing-pieces are so shaped that when placed around the periphery of the barrel they form, practically, a solid wall, constituting a compressor around said 80 barrel, as shown in Fig. 6. The lower half of these bearing-pieces C is cut away or flared outward, so that when they are moving downward with the arms they gradually impinge against the staves and bring them all together, 85 as some of the staves flare outward more than others. These bearing-pieces are also beveled at their upper inner edge, so that the hoop can be placed on the barrel more readily. These bearing-pieces may be made of any 90 size and of any other form and shape than the ones herein shown.

The arms B at their upper extremity, where the bearing-pieces are attached, are of a peculiar construction, being of spear-head shape 95

D and having a shoulder or offset E. The upper part of these arms B may, however, be differently shaped. They are so shaped to enable the ring to more readily slip down over them.

F represents a ring, which is suitably hinged on one of the arms B, as shown in Fig. 1. It may be otherwise connected. This ring may be counterbalanced in any suitable manner. 10 This ring slips over the arms B and lodges in the offset E in said arms to hold said arms and bearing-pieces together, as shown in Figs. 4, 5, and 6. The ring is held in this position by a locking device G. The ring slips down over 15 these top parts of the arms B easily on account of the peculiar construction of the top portion of the arms at D. The ring may be operated in any other manner. The bearing-pieces and arms may also be held together 20 or against the barrel in any other suitable manner.

When the barrel has been placed in proper position, and the arms carrying the bearing-pieces have been brought together and the 25 ring has been placed around them, all that is necessary is to hold the head in the barrel opposite the croze in the staves and operate the machine downward. This downward movement carries the arms, bearing-pieces, 30 and ring downward, forcing the chucks against the staves of the barrel, the lower the parts descend the tighter they impinge, as the bilge of the barrel becomes more marked. Consequently the staves are forced inward and together, and the head into the croze in the 35 staves. The hoop may then be placed on the barrel. The ring is then unlocked and it is pulled upward, being counterbalanced. The arms B can then be raised and forced outward, so that the barrel can be taken out to be 40 headed at its opposite end.

In order to place the barrel in and out, one of the arms can be moved backward farther than the other arms on account of the slot H (see Fig. 6) being elongated, the other arms 45 passing through similar but shorter slots.

I shall now describe the mechanism for bringing the arms B up and down and inward and outward. This mechanism may be 50 changed, if desired.

K represents the floor of the shop, through which pass the arms B, slots being provided for that purpose. The lower ends of the arms B are connected to a plate L in any suitable 55 manner. This plate has three arms M, which have sleeves, as N, which slide up and down on the uprights or standards O, which standards are attached at the top and bottom to plates P P. (See Figs. 1 and 2.) A screw-shaft 60 R extends between the plates P P and is suitably journaled in boxes S. This screw-threaded shaft passes through the plate L, (through a screw-threaded opening therein.) On said shaft R is connected the gear-wheel 65 T. On a shaft V are connected two friction-disks W and a pulley X. This shaft is journaled in boxes Y, a lever Z being attached to

the shaft V at one end to throw said disks W in and out of contact with the friction-disk A', which is connected to one end of a shaft 70 B'. (See Fig. 2.) This shaft B' is journaled in the boxes C', and carries at its inner end the pinion-wheel D', which meshes with the gear-wheel T on shaft R. These parts operate as follows: A belt passes over the pulley 75 X, imparting motion to it and to the shaft V, the friction-disks W W revolving therewith, and said shaft V, being loosely journaled in the boxes Y Y, can be moved forward and backward, thus throwing one of the disks W 80 in contact with the disk A' and one out of contact therewith. Motion being thus imparted to the disk A', the shaft B', on which it is connected, also revolves, consequently imparting motion to the pinion-wheel D', 85 which is also on said shaft B', and said wheel D', meshing with the gear-wheel T, imparts motion to it, said gear-wheel T in turn revolving the screw-threaded shaft R, on which it is keyed. This shaft R, working in the screw-threaded opening in plate L, moves said plate up or down at the will of the operator, throwing one or the other of said disks W in contact with disk A', and the arms B, being attached to the plate, move up or down with it. 90 The arms B may be thrown in or out simultaneously. This is accomplished as follows:

E' represents a disk pivoted on the top plate P. To this disk are pivotally attached one end of the arms or straps G'. The other ends of these arms are slotted, and the arms B pass through this slotted portion. These straps or arms G' are so pivoted to the disk E' as to be on a line out of the center of the pivotal point of said disk E', so that when one arm B is pushed inward it revolves the disk E' to the left, consequently pulling the other arms B inward, as they are all similarly connected to the disk E', and by pulling one of the arms B outward revolves said disk E' in 110 an opposite direction, and all the arms are forced outward.

The barrel is headed as follows: When the arms are in the position shown in Fig. 1, one of them (the one in the elongated slot H, as seen in Fig. 6) is thrown down and the barrel A placed on the platform K', the top truss-hoop having been removed from the barrel. The arm B in slot H is then again thrown back and all the arms are consequently thrown inward, as shown in Fig. 4, so that the ring can be pulled down by the operator and placed in the offsets E, which is now done. The machine has now assumed the shape shown in said Fig. 4. The operator then takes a 125 punch and forces it into the head of the barrel and places it into the barrel opposite the croze cut in the staves, as shown in Fig. 4. With his other hand he moves the lever Z in the proper direction, so that the arms will 130 be forced to move downward. This downward movement is continued until the parts assume the shape shown in Fig. 5, where it will be seen that the head has been forced into

the croze in the staves. It will also be seen that the arms, bearing-pieces, and ring have moved downward far enough to allow of a hoop being placed on the barrel. (See Fig. 5.) When said hoop has been placed thereon, the ring F is released and it assumes its former position. (See Fig. 1.) The lever Z is reversed, the arms B, carrying the bearing-pieces, move upward, and the barrel can be removed. In the downward movement, just above described, the bearing-pieces C impinge against the barrel to force the staves inward and together, they being retained in position by the ring F. As they move downward, the pressure against the barrel is greater as the barrel widens, (the bilge becoming greater.) This downward movement is continued until the head is in, when it is stopped, the hoop being then put on.

20 The ring F could be omitted and other mechanism used to keep the bearing-pieces in position. One form is shown in the modifications in Fig. 9, where the arms are forced to travel against rollers M' in brackets N', rigidly secured to the floor or platform. The arms would in this case be of a peculiar construction, as shown, having a greater degree of curvature, so that when they were moving downward they would also be forced inward

25 and against the barrel, consequently allowing the bearing-pieces to force the staves inward and together.

It is obvious that other mechanism could be employed, and other mechanism might be directly connected to the bearing-pieces to keep them in position.

The main feature of my invention consists in providing a series of bearing-pieces to form a solid wall around the barrel when brought together, only small spaces being left between the chucks when desired, and holding said bearing-pieces in that position as they move downward over the periphery of the barrel. I preferably employ the mechanism as described; but I may use only one or more of said parts of my invention, and may use them in connection with barrel-heading machines of a form other than the one herein described.

What I claim as new and of my invention, and desire to secure by Letters Patent, is—

1. In a barrel-heading machine, a series of bearing-pieces mounted upon pivoted arms and constituting a compressor, means for bringing the bearing-pieces inward to encircle and bear against all the staves of the barrel at its periphery, and devices for holding said bearing-pieces rigidly in position against the staves while moving downward, in combination with mechanism for moving the compressor downward, substantially as described.

2. In a barrel-heading machine, a series of bearing-pieces constituting a compressor and pivoted arms supporting the bearing-pieces, in combination with a ring encircling the bearing-pieces and holding them in position around the periphery of the barrel and operating mechanism for moving said compressor downward, substantially as described.

3. In a barrel-heading machine, a series of independently-mounted bearing-pieces constituting a compressor, the said bearing-pieces having concave inner surfaces, and a ring encircling the bearing-pieces and holding them against the periphery of the barrel, in combination with operating mechanism for moving the compressor upward and downward, substantially as described.

4. In a barrel-heading machine, a series of bearing-pieces supported on arms having a spear-shaped head and an offset E, in combination with a ring, as F, substantially as set forth.

5. In a barrel-heading machine, a series of bearing-pieces mounted on arms, as B, in combination with a counter-balance, and a ring, as F, hinged to one of said arms, substantially as set forth.

Signed at Cincinnati, Ohio, this 31st day of May, A. D. 1890.

JOHN J. MULVANEY, JR.
